HATCH CONSTRUCTION

Charles David Bonsall, Pittsburgh, Pa., assignor
to P. H. Murphy Company, New Kensington,
Pa., a corporation of Pennsylvania

Application September 4, 1937, Serial No. 162,414

10 Claims. (Cl. 108—5.4)

This invention relates to the hatch construction of a railway car, particularly the hatch constructions of a refrigerator car roof. A common type of hatch construction for such roofs includes a wooden hatch frame, an insulated plug therefor and a metal hatch frame or liner that extends below said plug and thus serves to conduct outside heat into the interior of the car.

The principal object of the present invention is to devise a simple, economical and durable hatch construction that will prevent the transfer of heat by the metal hatch frame or liner past the hatch plug. The invention consists in the hatch construction and in the parts and in the combinations and arrangements of parts herein-after described and claimed.

In the accompanying drawing, which forms part of this specification and wherein like symbols refer to like parts wherever they occur,

Fig. 1 is a vertical transverse section through a portion of a car roof provided with a hatch construction embodying my invention;

Fig. 2 is a vertical longitudinal section through the roof on the line 2—2 in Fig. 1; and

Figs. 3 and 4 are views similar to Figs. 1 and 2, respectively, illustrating a modified form of the invention.

In the accompanying drawing, my invention is illustrated in connection with a metal refrigerator car roof comprising an end roof sheet 1 and an intermediate roof sheet 2 that have their eaves end portions supported on and secured to an eaves angle 3 that is fixed to the side plate 4 of the car. Said end and intermediate roof sheets are provided along their adjacent margins with upstanding flanges 5 that are covered and secured together by a seam cap 6. At the end of the car, the end sheet 1 is secured to an end angle 7 fixed to a metal end plate 8.

The roof is provided with a hatchway that leads downwardly into the interior of the car through hatch openings provided therefor in the end roof sheet 1 and a frame 9 of wood or other suitable non-metallic material located therebelow. A metal hatch frame or liner 10 preferably comprises a relatively wide upper portion 11 located above the general level of the roof, a relatively narrow lower portion 12 that fits within the upper portion of the wooden hatch frame 9, and a shoulder or web portion 13 that rests upon the top of said wooden hatch frame. As shown in the drawing, the wide upper portion 11 of the metal hatch frame 10 has upwardly converging side walls that terminate at the top of said frame in an inturned flange 14 that has a

downturned lip and constitutes a seat for a suitable hatch cover (not shown); and the narrow lower portion 12 of said frame has downwardly converging side walls that form the upper portion of a tapered seat or a tapered insulated hatch plug 15.

The end roof or hatch sheet 1 is provided around the hatch opening therein with an up-standing flange 16 that is secured to the outer faces of the upwardly converging side walls of the wide upper portion 11 of the metal hatch frame 10 by a weld 16a that extends continuously along the top edge of said flange.

The lower portion of the tapered hatch plug seat is formed by a frame or insert 17 of mahogany or other hard non-metallic material adapted to resist wear, warping, moisture and decay. This hardened frame fits within a channel 18 provided therefor inside the wooden hatch frame 9 and forms a flush continuation of the lower hatch plug seat portion of the metal hatch frame or liner 10. The wooden hatch frame 9 is provided below the mahogany or other hardwood insert with a metal frame or liner 19 whose lower portion is bent outwardly beneath the ceiling 20 of the car and whose upper portion is bent into the form of a channel 21 that snugly fits within said channel 18 beneath the hardwood filler or insert 17 therein.

In the modification shown in Figs. 3 and 4, the entire lower portion of the opening in the wooden hatch frame 9a is lined with mahogany tongue-and-grooved boards 17a that fit within a recess 18a provided therefor in said frame and are disposed flush with and form a continuation of the inner surface of the downwardly and inwardly inclined narrow lower portion 12 of the metal hatch frame 10. This mahogany liner 17a extends above the lower edge of the metal hatch frame 10; and a layer of waterproof insulating paper 19a is interposed between said liner and the recess 18a provided therefor in the wooden hatch frame 9a.

The hereinbefore described hatchway construction has several advantages. The metal hatch frame or liner terminates short of the bottom of the insulated hatch plug insert of wood and is disposed flush with the plug seat-forming portion of the mahogany filler or insert in the wooden hatch frame, thereby preventing the metal hatch frame from transmitting heat between the spaces above and below said hatch plug. The mahogany insert or filler provides a smooth surface for obtaining a close fit of the hatch plug therein; it also provides a hard, smooth wear-re-

sistant surface; and it also serves, in the construction shown in Figs. 1 and 2, as a means for firmly anchoring the upper portion of the lower metal liner or frame to the wooden hatch frame. In the construction shown in Figs. 3 and 4, the mahogany insert or liner for the wooden hatch frame extends clear to the lower end thereof and thus serves after the manner of the lower metal liner or frame of Figs. 1 and 2 as a wear member for said frame; and the strip of paper interposed between said frame and said liner serves as an insulator and to protect the wooden hatch frame against moisture.

What I claim is:

15. 1. A hatch construction for a railway car comprising a non-metallic hatch frame, an insulated hatch plug, and a metallic hatch frame or liner fitted in said main frame and cooperating therewith to form the outer end portion only of a seat for said hatch plug.
20. 2. A hatch construction for a car roof comprising a non-metallic hatch frame, a non-metallic hatch plug, and a metallic hatch frame or liner extending downwardly into said non-metallic hatch frame, said non-metallic hatch frame forming the lower portion of a seat for said hatch plug and said metallic hatch frame forming the upper portion of said seat.
25. 3. A hatch construction for a refrigerator car roof comprising a non-metallic hatch frame, a plug therefor, and a metallic frame or liner extending downwardly into said non-metallic hatch frame and cooperating therewith to form the upper portion only of a seat for said plug.
30. 4. A hatch construction for a refrigerator car roof comprising a non-metallic hatch frame, an insulated hatch plug, and a metallic frame or liner extending downwardly into said non-metallic hatch frame and cooperating therewith to form a seat for said hatch plug, the lower plug seat-forming portion of said metallic frame terminating short of the underside of said plug and flush with the seat-forming portion of said non-metallic hatch frame, thereby preventing transmission of heat by said metallic frame past said plug.
35. 5. A hatch construction for a refrigerator car roof comprising a non-metallic hatch frame, a metallic frame or liner fitting in said main frame and terminating short of the lower end thereof, and an insulated hatch plug having its upper portion seated in the lower portion of said metallic frame and its lower portion seated in the portion of the non-metallic hatch frame located therebelow.
40. 6. A hatch construction for a refrigerator car roof comprising a non-metallic hatch frame having a recess in the inner face thereof, a filler mounted in said recess, a metal frame or liner extending downwardly into said non-metallic hatch frame in flush overlapped relation with the upper portion of said filler, and a hatch plug having its upper portion seated in said metal hatch frame or liner and its lower portion seated in said filler.
45. 7. A hatch construction for a railway car comprising a wooden hatch frame having a recess in the inner face thereof, a hardwood filler mounted in said recess, a metal hatch frame or liner extending into the outer end of said wooden hatch frame in flush overlapped relation with the outer end of said hardwood filler, and a hatch plug having its outer end portion seated in the inner end of said metal hatch frame or liner and its inner end seated in said hardwood filler.
50. 8. A hatch construction for an insulated car roof comprising a non-metallic hatch frame, a metallic hatch frame or liner fitting in said non-metallic hatch frame and terminating short of the lower end thereof, and an insulated hatch plug having its upper portion seated in the lower portion of said metallic hatch frame and its lower portion seated in the portion of the non-metallic hatch frame located therebelow.
55. 9. A hatch construction for an insulated car roof comprising a non-metallic main frame having a channel in the inner face thereof, a metallic frame or liner fitting in said main frame and terminating adjacent to the upper edge of said channel, a non-metallic filler in said channel, an insulated hatch plug having its upper portion seated in the lower portion of said metallic frame and its lower portion seated in said filler, and a metal liner for said channel and the portion of the non-metallic main frame located therebelow.
60. 10. A hatch construction for a refrigerator car roof comprising a non-metallic hatch frame having a recess in the inner side thereof, a non-metallic filler in said recess, a metallic hatch frame or liner fitting in said non-metallic hatch frame with its lower end terminating adjacent to said filler, an insulated hatch plug having its upper portion seated in the lower portion of said metallic hatch frame and its lower portion seated in said filler, and a layer of waterproof material interposed between said recess and said filler.

CHARLES DAVID BONSALL.
